ABSTRACT OF THE DISCLOSURE

An electrical switch assembly having movable contact members mounted in aligned apertures of spaced plates which can be readily assembled and disassembled from the switch assembly.

BACKGROUND OF THE INVENTION

The present invention relates to an electrical switch assembly including a movable contact member made of leaf spring fixed at its base end, a fixed contact member arranged under the movable contact member near its free end and an actuator for depressing said movable contact member to move the free end into contact with said fixed contact member.

The switch assembly of such construction is suitable for a key switch of an electronic musical instrument.

In the conventional switch assembly heretofore used in the electronic musical instrument, the movable contact member or members are fixed at its base ends to a switch frame by soldering. Accordingly the assembling of the movable contact members is troublesome and time-consuming and, after assembled, they cannot be easily disassembled from the switch frame.

SUMMARY OF THE INVENTION

It is an object of the present invention to provide an electrical switch assembly in which a movable contact member or members can be very easily assembled in the switch assembly by a simple operation.

It is another object of the present invention to provide an electrical switch assembly in which a movable contact member or any of movable contact members can be very easily disassembled from the switch assembly.

In accordance with the present invention there is provided an electrical switch assembly comprising a movable contact member made of leaf spring having a notched part near its base end, a fixed contact member arranged under a free end of the movable contact member, an actuator for depressing said movable contact member to move the free end into contact with said fixed contact member, and front and rear supporting plates spaced apart from each other and fixed in the assembly, said supporting plates have aligned apertures for receiving the base portion of the movable contact member, one of said apertures having a recess at the side thereof for receiving said notched part of the movable contact member to secure its longitudinal position, said front supporting plate urging the movable contact member upward and said rear supporting plate urging the movable contact member downward.

BRIEF DESCRIPTION OF THE DRAWINGS

The drawings illustrate a preferred embodiment of the present invention in which:

FIG. 1 schematically shows a key switch for an electronic musical instrument embodying the present invention;

FIG. 2 is an exploded perspective view of essential parts of FIG 1; and

FIG. 3 is a similar perspective view showing a modified form.

2

DESCRIPTION OF THE PREFERRED EMBODIMENT

FIG. 1 shows a key switch assembly for an electronic musical instrument according to the present invention. The switch assembly includes movable contact members 1, fixed contact members 2 and an actuator 3. When the actuator 3 is depressed by a key shown by a broken line 4, it moves the movable contact members 1 into contact with the corresponding fixed contact members 2.

The key switch according to the present invention comprises front and rear supporting plates 5 and 5' spaced apart from each other and fixed in the switch assembly, said supporting plates 5 and 5' having aligned apertures 6 and 6' for receiving the movable contact member 1, said apertures having recesses 7 and 7' at their one sides, respectively. The movable contact member 1 has a notched part 8 at its base portion. Counter contact members 9 are arranged above the respective free ends of the movable contact members. Each of the movable contact members 1 is inserted through the aligned apertures 6 and 6' of the pair of parallel supporting plates 5 and 5', and through an opening 10 of the actuator, and the free end of the movable contact member resiliently bears against the corresponding counter contact member 9 by its own elasticity.

The movable contact member 1 shown in the drawings has a bent portion and is forcibly passed through the aligned openings 7, 7' and 10, whereby the front supporting plate 5 urges the movable contact member 1 upward and the rear supporting plate 5' urges the same downward, thereby biasing the free end upward.

The notched part 8 of the movable contact member 1 is fitted in the recess 7 at the side of the aperture 6 of the front supporting plate 5 whereby the longitudinal position of the member 1 is secured. The side part of the movable contact member 1 is supported by the full width of the aperture 6' of the rear supporting plate 5'. Thus the movable contact member is fixedly supported at its base portion by the pair of supporting plates 5 and 5'.

Although in the form shown in FIG. 2 the recesses 7 and 7' are formed in the lower sides of the apertures 6 and 6', respectively, these recesses may be formed in the upper sides of the apertures 6 and 6'. Such a modified form is shown in FIG. 3. In this modified form, the notched part 8a of the movable contact member 1a is fitted in a recess 7a' formed in one side of an aperture 6a' of a rear supporting plate 5a' and wide part of the contact member 1a is supported by the full width of an aperture 6a of a front supporting plate 5a.

The apertures 6 and 6' have a width slightly wider than that of the movable contact member, and the recesses 7 and 7' have a width slightly wider than that of the notched part 8, while a length of the notched part 8 is slightly wider than the thickness of the front supporting plate, so that the movable contact member snugly fits in the aperture of the rear supporting plate and in the recess of the aperture of the front supporting plate, whereby the movable contact member is firmly held by the supporting plates 5 and 5'.

In the drawings the engagement of the movable contact member 1 with the rear supporting plate 5' is made between the wide part of the movable contact member 1 and the full width of the aperture 6', so that it is not always necessary to form the recess 7' in the aperture 6' of the supporting plate 5'. By using same shape of the supporting plate 5' as that of the supporting plate 5 the manufacturing cost can be substantially reduced.

It will be understood from the above description that according to the present invention the movable contact member can be easily assembled in the electrical switch assembly by inserting the member through the aligned apertures in the pair of parallel supporting plates and the opening in the actuator and, after assembled, it can

be easily disassembled from the switch assembly as desired. This structure can be easily manufactured by forming notches at the side edges of the movable contact member made of leaf spring so as to form the narrow part therein, without requiring any special treatment.

What is claimed is:

1. An electrical switch assembly comprising a movable contact member made of leaf spring having a notched part near its base end, a fixed contact member arranged under a free end of the movable contact member, an actuator movably mounted in the assembly for depressing said movable contact member to move the free end into contact with said fixed contact member, and front and rear supporting plates spaced apart from each other and fixed in the assembly, said supporting plates have aligned apertures receiving the base portion of the movable contact member, one of said apertures having a recess at the side thereof receiving said notched part of the movable contact member to secure its longitudinal position, said

5

10

front supporting plate urging the movable contact member upward and said rear supporting plate urging the movable contact member downward.

2. An electrical switch assembly according to claim 1, in which the recess is formed at the lower side of the aperture provided in the front supporting plate.

3. An electrical switch assembly according to claim 1, in which the recess is formed at the upper side of the aperture provided in the rear supporting plate.
